UNITED STATES PATENT OFFICE.

HARRY C. STOLZ, OF FRANKLIN, PENNSYLVANIA.

TWO-CYCLE ENGINE.

Application filed March 16, 1925. Serial No. 15,890.

This invention has particular reference to a two-cycle, internal combustion engine of the three-port valveless type, such as are commonly used in oil field operation and are operated either on liquid fuel or natural gas. In this type of engine the engine fly wheel is initially rocked to build up a combustible charge in the pump chamber and introduce it into the combustion chamber.

10 In larger engines, especially, this preliminary rocking, incidental to starting, is quite a task because of the resistance offered by the gases compressed ahead of the piston before the piston reaches the intake ports to 15 uncover them. It is known in the art, to arrange auxiliary gas and air intake ports in advance of the main ports whereby a preliminary charge may be secured without 20 rocking the fly wheel to the full extent needed to uncover the main intake ports.

The object of my invention is to provide means for starting a three-port, two-cycle gas engine by rocking, and in such manner as to eliminate the complication of piping 25 and mixing valve, danger from fire and explosion without sacrifice of constant mixture both in starting and regular operation of engine, in a more advantageous way than heretofore devised.

30 I am aware that various means of starting this type of gas engine by rocking have been invented but heretofore, in certain engines there has been but one auxiliary inlet provided in the cylinder for both gas and air, 35 with more or less external piping and valves to control the gas and air, which as a whole are but crude forms of mixing valves.

Among the objections to such known constructions is the dangerous amount of gas 40 passing out through the auxiliary air intake to the atmosphere while starting the engine, and the blowing out of a part of the charge after engine is started and before the auxiliary cocks are closed.

45 The invention further resides in the salient features of construction, and the arrangements and combinations of parts described in detail in the following description and defined in a succinct manner in the 50 appended claims reference being made to the accompanying drawing wherein

Fig. 1 is a fragmentary longitudinal sectional view of the cylinder constructed in accordance with the present invention;

Fig. 2 is an elevation thereof; 55

Fig. 3 is a longitudinal section through the engine with the piston which is shown partly in elevation, at its full compression;

Fig. 4 is a fragmentary longitudinal section depicting the piston at its full expansion; 60

Fig. 5 is a similar view wherein the piston is about to uncover the auxiliary intake ports;

Figs. 6 and 7 are respectively transverse sections on lines 6—6 and 7—7 of Fig. 3; 65

Fig. 8 is a diagrammatic view indicating the path of the engine crank shaft; and

Fig. 9 is a detailed section illustrating means for completely closing the auxiliary 70 intake ports.

The cylinder 1 is provided with the piston 2, the skirt of which is designed to uncover the gas intake port 3 and an air intake port 4 upon each forward reciprocation to admit 75 of a charge being admitted into the pump chamber 5 to be transferred subsequently through the transfer port 6 to the combustion chamber 7, such transfer being effected by reason of the piston, on its rearward or return reciprocation, closing the ports 3 and 4 and acting in the capacity of a pump to 80 compress the gaseous mixture in said chamber 5 so that the said mixture will readily escape into the combustion chamber as the piston uncovers the transfer port 6. The 85 exhaust gases escape from the combustion chamber through the exhaust port 8.

The foregoing is more or less common in two cycle engines of the three-port type, and 90 in rocking the fly wheel it has been necessary to uncover the intake ports which operation required the piston to be moved against an excessive head pressure; quite a task for man power. Recent patents disclose the use 95 of auxiliary intake ports which the piston uncover prior to uncovering the main ports, and which require a relatively small amount of man power.

My present invention is an improvement 100 on my prior Patent No. 1,203,807, dated November 7, 1918, and comprises an auxiliary air intake port 9 and an auxiliary intake port 10 in each of which is secured an inwardly opening check valve 11. The check valves 105 project outwardly and are housed within manifold-like chambers 12 and 13 for which chambers also respectively lead the gas in-

take port 3 and the air intake port 4. A plurality of air intake ports 4 are provided in communication with the manifold chamber 13 and are in relative circumferential alinement.

Referring to Fig. 8, the circle indicates the movement of the crank shaft to which the piston rod 14 is linked in the usual manner, the wrist pin 15 being rocked from position *a* to position *b* to uncover the auxiliary intake ports as against the greater amplitude which would closely approach position *c* required to uncover the main intake ports. After the engine has been started the major portion of the charge will be admitted through the main intake ports although a portion of the charge will enter through the auxiliary ports. As the piston begins to compress its charge in chamber 5 the check valves immediately close so as to prevent the escape of any portion of the charge through the auxiliary ports before the piston covers the same.

After the engine has been started both auxiliary valves are readily closed by manually adjustable valves 16 which are threaded through a removable wall plate 17 for adjustment toward and from the casing of the respective check valve for closing the inlet side thereof whereupon the auxiliary ports are rendered completely inoperative for normal running of the engine.

What is claimed is:—

1. In a two-cycle engine of the three-port valveless type having air and gas intake ports covered and uncovered by the engine piston, a manifold chamber for each the air and gas intake ports, and an auxiliary intake port leading from each chamber into the engine cylinder rearwardly of the first ports and adapted to be covered and uncovered by the piston.

2. In a two-cycle engine of the three-port valveless type having air and gas intake ports covered and uncovered by the engine piston, a manifold chamber for each of the air and gas intake ports, an auxiliary intake port leading from each chamber into the en-

gine cylinder rearwardly of the first ports and adapted to be covered and uncovered by the piston, and inwardly opening check valves arranged in each auxiliary port.

3. In a two-cycle engine of the three-port valveless type having air and gas intake ports covered and uncovered by the engine piston, a manifold chamber for each the air and gas intake ports, an auxiliary intake port leading from each chamber into the engine cylinder rearwardly of the first ports and adapted to be covered and uncovered by the piston, inwardly opening check valves arranged in each auxiliary port, and manual means for rendering the auxiliary ports inoperative.

4. In a two-cycle engine of the three-port valveless type having air and gas intake ports covered and uncovered by the engine piston, a manifold chamber for each the air and gas intake ports, an auxiliary intake port leading from each chamber into the engine cylinder rearwardly of the first ports and adapted to be covered and uncovered by the piston, inwardly opening check valves arranged in each auxiliary port, the outer end of the casing of each check valve providing a valve seat, and a manual valve for engaging on said seat to close the valve passage.

5. In a two-cycle engine of the three-port valveless type having air and gas intake ports, an auxiliary intake port leading into the engine cylinder rearwardly from each of the first ports, inwardly opening check valves arranged in each auxiliary port, and manual means for rendering the auxiliary ports inoperative.

6. In a two-cycle engine of the three-port valveless type having air and gas intake ports, an auxiliary intake port leading into the engine cylinder rearwardly of each of the first ports, a check valve arranged in each auxiliary port, the outer end of the casing of each check valve providing a valve seat, and a manual valve for engaging on said seat to close the valve passage.

In testimony whereof I affix my signature.

HARRY C. STOLZ.
